TOY GLIDER

Eugene J. Kilroy, Inglewood, Gerald K. Leistikow, San Pedro, and Philip B. Du Breuil, Redondo Beach, Calif., assignors to Mattel, Inc., Hawthorne, Calif.

Filed May 4, 1973, Ser. No. 357,404

Term of patent 14 years

Int. Cl. D21—01

U.S. Cl. D34—15 AF

FIG. 1 is a left perspective view from the bottom of a toy glider, showing our new design; and

FIG. 2 is a top plan view of the toy glider of FIG. 1 on a reduced scale.

The right perspective view from the bottom of the toy glider is substantially a mirror image of FIG. 1.

We claim:

The ornamental design for the toy glider, as shown and described.
